Ebenstein LLP

(57) **CLAIM**

The ornamental design for a lighting element, as shown and
described.

DESCRIPTION

FIG. 1 is a perspective view of a lighting element showing
my new design;

FIG. 2 is a side view thereof;

FIG. 3 is a front view thereof;

FIG. 4 is an opposite side view thereof;

FIG. 5 is a rear view thereof;

FIG. 6 is a bottom view thereof; and,

FIG. 7 is a top view thereof.

The broken lines in FIGS. 1-7 represent environmental
structure which forms no part of the claimed design.
